VAGINAL ATOMIZER

Richard O. Preston, Topeka, Kans.

Application August 5, 1932, Serial No. 627,649

2 Claims. (Cl. 128—232)

The present invention relates to improvements in surgical instruments and has reference more particularly to a vaginal atomizer.

The primary object of the present invention is to provide a device for treating vaginal diseases by the application of atomized medicated fluid and this in a positive and efficient manner.

One of the important objects of the present invention is to provide a vaginal atomizer of the above mentioned character wherein the application of medicinal agents to the entire mucous membrane of the vaginal tract and the cervix uteri can be accomplished in such a manner as not to cause a local over dosage.

15 A still further object is to provide a vaginal atomizer having a dilator structure associated with the tube, so that the application of the treatment may be had to such extent that all the folds of the vaginal canal are eliminated 20 while the medical agents are being applied directly to the diseased mucous membrane and the cervix uteri.

25 A still further object is to provide a vaginal atomizer of the above mentioned character that is adapted to be detachably associated with the spray nozzle of the well known "De Vilbiss" atomizer, the parts of my device being of such construction as to permit the same to be readily assembled and disassembled for cleaning purposes and sterilization.

Other objects and advantages of the present invention will become apparent when taken in connection with the accompanying drawings.

In the accompanying drawings, forming a 35 part of this application, and in which like numerals designate corresponding parts throughout the several views:

Figure 1 is a side elevation of the vaginal atomizer embodying my invention, showing the 40 dilator in its contracted position;

Figure 2 is a longitudinal sectional view taken approximately on the line 2—2 of Figure 1;

Figure 3 is a view similar to Figure 1 showing the dilator in its expanded position;

45 Figure 4 is a vertical sectional view taken approximately on the line 4—4 of Figure 3, looking in the direction of the arrows; and

Figure 5 is a similar section taken substantially on the line 5—5 of the same figure and also 50 looking in the direction of the arrows.

In the drawings, wherein for the purpose of illustration is shown the preferred embodiment of my invention, the numeral 1 designates generally a spray atomizer of the "De Vilbiss" type, the same including a receptacle 2 adapted to con-

tain a suitable liquid to be atomized or vaporized. The body of the atomizing tube which is threaded or otherwise secured to the receptacle 2 is indicated generally at 3. The atomizing tube that is carried by the body 3 comprises a pair of 60 spring tubular arms 4, the same having associated with the outer free ends thereof the nozzle 5. The atomizer 2, of course, has communication with the contents of the receptacle 2 and the usual pneumatic bulb that is attached 65 to the body of the atomizing tube, so as to force air, in the usual manner, into the receptacle so as to force the liquid upwardly through the tube and into the atomizing tube is shown at 6.

My attachment for this type of spray atomizer 70 comprises an elongated metallic vaporizing tube 7 that slidably fits over the tube of the atomizer 1 and is frictionally held thereon by reason of the outward springing of the hollow arms of the atomizing tube. The forward end of the 75 metallic vaporizing tube 7 has formed thereon the enlarged nozzle 8, the same being provided with the restricted discharge opening 9 at its forward end.

For the purpose of additionally securing the 80 metallic tube in position on the atomizing tube 4, the rear end of the vaporizing tube 7 is formed with the spring clip 10, formed by providing the rearwardly extending lip at the top of the rear end portion of the metallic tube and curving 85 the free end of this lip downwardly and then upwardly in the manner as readily obvious from the construction shown in Figures 1 and 3 of the drawings. This spring clip 10 engages with the top of the body 3 in the manner as also shown 90 very clearly in Figures 1 and 3. A protuberance 11 is formed on the top of the metallic vaporizing tube 7 adjacent the open rear end thereof for a purpose to be presently described.

As is more clearly illustrated in Figure 2 of 95 the drawings, the atomizing nozzle 5 is located in close proximity to the discharge opening 9 of the nozzle 8. Upon referring to the same figure, it will also be observed that the bottom portion of the rear end of the metallic vaporizing 100 tube 7 is cut away in order to permit the rear end portion of this tube to fit around the adjacent portion of the body 3 when the vaporizing tube 7 is positioned on the hollow arms of the atomizing tube 4.

105 Fixedly arranged on the intermediate portion of the metallic tube 7 is the expansion disk or plate 12, the same being formed with an annular series of spaced openings 13 to permit backflow of the fluid when the atomizer is in use.

Cooperating with the stationary disk or plate 12 is an expansible and contractible dilator denoted generally by the numeral 14. This dilator includes a collar 15 that is slideable on the rear 5 end portion of the metallic vaporizing tube 7 between the protuberance 11 and the fixed disk or plate 12. A series of spring dilating arms 16 have their free ends extending radially into the periphery of the collar 15, these spring arms extending forwardly and surrounding the vaporizing tube 7 and the disk 12, the forward free ends 10 of the arms terminating in curved finger portions 17 in the conventional manner.

As is shown more clearly in Figures 1 and 2, 15 the dilator 14 is in its contracted position and the finger portions 17 extend beyond the nozzle 8. However, when the dilator is moved rearwardly to the position shown in Figure 3, the disk or plate 12 will engage the spring arms 16, 20 causing the same to expand radially and when in this position, the finger portions 17 will be disposed circumferentially around the nozzle 8.

With the parts arranged as shown in Figure 25 3, the device is then ready for use.

A vaginal atomizer of the above mentioned character will insure positive and efficient medicamentation of the mucous membrane surfaces of the vaginal canal and the cervix uteri and in such manner that no local overdosage will occur.

The dilator will eliminate all folds of the vaginal canal while the medical agents are being applied directly to the diseased mucous membrane and furthermore, the medication will be entirely atomized or vaporized before it comes 30 in contact with the mucous surface of the entire vaginal wall.

The simplicity of my device enables the parts to be readily and easily assembled or disassembled for sterilization purposes and furthermore, the metallic tube and dilator can be readily and easily attached to or removed from a "De Vilbiss" atomizer.

While I have shown the preferred embodiment 40 of the invention, it is to be understood that minor changes in the size, shape and arrange-

ment of parts may be resorted to without departing from the spirit of the invention and the scope of the appended claims.

Having thus described the invention, what I claim is:

1. In combination with an atomizer including a liquid receptacle, an atomizer body thereon, and an atomizer tube extending from the body and including a pair of hollow spring arms having connection at their forward end with a spray nozzle; a vaporizing tube slidably fitted over the hollow arms of the atomizer tube and held thereon by the expansion of the hollow arms, and a nozzle formed on the forward end of the vaporizing tube and enclosing said spray nozzle, and a spring clip formed on the rear end portion of the vaporizing tube and bearing upon the top face of the atomizer body for additionally supporting the vaporizing tube on the atomizer. 80 85 90 95

2. In combination with an atomizer including a liquid receptacle, an atomizer body thereon, and an atomizer tube extending from the body and including a pair of hollow spring arms having connection at their forward end with a spray nozzle; a vaporizing tube slidably fitted over the hollow arms of the atomizer tube and held thereon by the expansion of the hollow arms, a nozzle formed on the forward end of the vaporizing tube and enclosing said spray nozzle, the rear end of the vaporizing tube being cut away to 100 form a spring clip at the top of the rear end portion of the vaporizing tube for engagement with the top of the atomizer body for additionally supporting the vaporizing tube on the atomizer, an expansible and contractible dilator slidably arranged on the vaporizing tube, an expansion disk fixedly secured on the intermediate portion of the vaporizing tube for expanding the dilator when the latter is moved in one direction, and a stop forming element projecting 105 from the rear end portion of the vaporizing tube 110 to limit the rearward sliding movement of said dilator. 115 120 125 130 135 140 145 150
